UNITED STATES PATENT OFFICE

119,510

DESIGN FOR A LUGGAGE CASE

George Henry Wheary, Racine, Wis., assignor to Wheary Trunk Company, Racine, Wis., a corporation of Wisconsin

Application June 16, 1939, Serial No. 85,516

Term of patent 7 years

To all whom it may concern:

Be it known that I, George Henry Wheary, a citizen of the United States, residing at Racine, in the county of Racine and State of Wisconsin, have invented a new, original, and ornamental Design for a Luggage Case, of which the following is a specification, reference being had to the accompanying drawing, forming part thereof.

The bottom of the case is plain and substantially similar in appearance to the top, and the side and end walls thereof opposite those illustrated in Figure 1 are identical in appearance to the side and end walls shown.

The dominant features of my design reside in the portions shown in full lines.

I claim:

The ornamental design for a luggage case, as shown and described.

GEORGE HENRY WHEARY.
